No. 898,046.

PATENTED SEPT. 8, 1908.

G. H. GUNVALSON.
BRACE AND PLATE.
APPLICATION FILED MAR. 23, 1908.

UNITED STATES PATENT OFFICE.

GUSTAVE H. GUNVALSON, OF MINNEAPOLIS, MINNESOTA.

BRAKE AND PLATE.

No. 898,046.

Specification of Letters Patent.

Patented Sept. 8, 1908.

Application filed March 23, 1908. Serial No. 422,857.

To all whom it may concern:

Be it known that I, GUSTAVE H. GUNVALSON, a citizen of the United States, residing at Minneapolis, in the county of Hennepin 5 and State of Minnesota, have invented a new and useful Brace and Plate, of which the following is a specification.

This invention relates to rail braces and has for its object to provide a strong, durable 10 and thoroughly efficient device of this character which serves the dual function of a bed plate and support for bracing the rail against lateral strains.

A further object of the invention is to provide a rail brace comprising a body portion 15 having its opposite longitudinal edges bent laterally to form reinforcing flanges and one end thereof reduced in width and bent upwardly to produce an over-hanging enlargement having a seating recess for the reception of the head of the rail.

A still further object of the invention is generally to improve this class of devices so as to increase their utility, durability and 20 efficiency as well as to reduce the cost of manufacture.

Further objects and advantages will appear in the following description, it being understood that various changes in form, proportions and minor details of construction 30 may be resorted to within the scope of the appended claims.

In the accompanying drawings forming a part of this specification: Figure 1 is a perspective view of a portion of a rail provided with a combined bed plate and brace constructed in accordance with my invention. Fig. 2 is a plan view of the blank from which the brace is constructed.

40 Similar numerals of reference indicate corresponding parts in all of the figures of the drawings.

The improved device forming the subject matter of the present invention is principally 45 designed for use in connection with rail-way rails and by way of illustration is shown in connection with a rail of the ordinary construction in which 5 designates the rail mounted on the usual cross tie 6.

50 The brace is preferably stamped or otherwise formed from a sheet metal blank 7 having its opposite longitudinal edges at one end thereof bent laterally to form reinforcing ribs or flanges 8 and its intermediate portion 55 curved inwardly to produce a reduced neck 9, the metal between the neck 9 and the

other end of the blank being curved laterally at 10 to produce oppositely disposed wings or flanges 11. One end of the blank 7 is provided with a plurality of openings 12 adapted to receive spikes or similar fastening devices 13, while the opposite end thereof is adapted to be bent laterally on the fold line 14 to produce an over-hanging arm 15 constituting a brace. The free end of the 65 brace 15 is provided with a square terminal adapted to bear against the adjacent side of the head of the rail, while the free end of the wings or flanges 11 are formed with recesses 16 adapted to register with each other when 70 the wings are bent laterally on the fold line 17 to accommodate the lower portion of the head of the rail. It will thus be seen that the over-hanging arm 15 bears against both the head and web of the rail and serves to reinforce and strengthen the latter and support the rail against lateral strains incident to the 75 passage of cars and other rolling stock.

Attention is here called to the fact that the longitudinal ribs or flanges 8 terminate at the 80 reduced portion of the neck 9, while the fold line 14 extends transversely across the blank at said neck so as to permit the metal to be readily folded laterally to produce the overhanging arm or brace 15.

85 By forming the intermediate portion of the blank with a reduced connecting portion or neck 9 when the arm 15 is folded into shape the latter will yieldably engage the head of the rail but at the same time will be sufficiently rigid to effectually resist any lateral strains or thrusts to which the rail may be subjected.

90 In constructing the brace the wings or flanges 11 are folded laterally on the lines 17 and the arm 15 bent upwardly on the fold line 14. The brace is then placed in position 95 on the cross tie 6 with the rectangular portion of the brace interposed between the base of the rail and the cross tie and with the head 100 of the rail seated in the recess 16, as best shown in Fig. 1 of the drawings. The bed plate is then rigidly secured to the cross tie by inserting the spikes 13 in the openings 12 and driving the same home with a maul or 105 other suitable tool. It will thus be seen that the body portion 7 forms a support or bed plate for the base of the rail while the overhanging arm 15 acts as a brace to maintain the rails in alignment and prevent spreading 110 of the same. It will also be noted that the lateral wings or flanges serve to reinforce and

strengthen the arm 15 while at the same time presenting spaced bearing surfaces for engagement with the head and flange of the rail.

5. From the foregoing description it will be seen that there is provided a comparatively simple and inexpensive brace which is strong in construction, light in weight and admirably adapted for the attainment of the ends in view.

10 Having thus described the invention what is claimed is:

15 1. A rail brace comprising a plate adapted to extend beneath and support the base of a rail, and having an intermediate portion thereof reduced in width and one end bent upwardly to form an over-hanging arm adapted to yieldably engage the head of the rail.

20 2. A rail brace comprising a plate adapted to extend beneath and support the base of a rail and provided with oppositely disposed depending reinforcing flanges, one end of the plate being reduced in width and bent upwardly to form an over-hanging arm having a seating recess formed therein for the reception of the head of the rail.

30 3. A rail brace comprising a plate adapted to extend beneath and support the base of a rail and provided with oppositely disposed longitudinal flanges, an intermediate portion of the plate being reduced in width to form a neck and one end of said plate bent to produce an over-hanging arm for engagement 35 with the head of the rail, the opposite longitudinal edges of the arm being bent downwardly to form spaced reinforcing flanges.

40 4. A rail brace comprising a plate adapted to extend beneath and support the base of a rail and provided with oppositely disposed

longitudinal reinforcing flanges, an intermediate portion of the plate being reduced in width to form a neck terminating in an over-hanging arm, the opposite longitudinal edges of which are provided with depending flanges, 45 there being seating recesses formed in said flanges for the reception of the head of the rail.

5. A rail brace comprising a plate provided with spike receiving openings and having an intermediate portion thereof reduced in width and bent upwardly over the perforated portion of the plate to form an over-hanging arm, the opposite longitudinal edges of the arm being bent downwardly to form 50 spaced reinforcing flanges the terminals of which are provided with seating recesses for the reception of the head of the rail.

6. A rail brace constructed from a metallic blank, the opposite longitudinal edges at one end of the blank being bent laterally to form depending reinforcing flanges, and an intermediate portion of the blank curved inwardly and reduced in width to form a neck, the longitudinal edges of the blank at said neck 55 being curved outwardly to form lateral wings, said wings being foldable laterally at each side of the blank, and the metal between said wings folded upwardly at the neck to produce an over-hanging arm, there being recesses formed in the free ends of the wings and adapted to register with each other when said wings are folded into shape.

In testimony that I claim the foregoing as my own, I have hereto affixed my signature 75 in the presence of two witnesses.

GUSTAVE H. GUNVALSON.
